CONTACT STRIP ANNEALING FURNACE

Raymond W. Cook, Bristol, Conn., assignor to
 Associated Spring Corporation, Bristol, Conn., a
 corporation of Delaware

Application August 17, 1942, Serial No. 455,103

3 Claims. (Cl. 266—3)

This application is a continuation in part of my co-pending application Serial No. 294,017, filed September 8, 1939, for Contact strip annealing furnace.

By the invention disclosed in this and the parent application I provide means for heating strip metal, in which two imperforate, endless metallic belts are mounted on pulleys so that parts thereof will be in opposed, face-to-face relation and will be spaced sufficiently to engage the opposite faces of a strip of metal passed therebetween, the belts and the strip being moved to cause the contacting parts thereof to travel together throughout a part of the total travel of the belts, and the belts being heated in order to transfer heat to the strip by conduction throughout the contacting length of the belts and strip.

In the use of vertical or inclined strip heating means according to my invention, in which the heating belts depend from supporting pulleys, it has been found that the belts, when heated, will be stretched by their own weight. It is the object of the invention described and claimed in this application to provide a furnace chamber within which the belts are positioned and which is formed with recesses or wells within which any slack due to stretching of the belts is received.

Other objects and features of novelty of the invention will be made apparent by the following description and the annexed drawing, it being clearly understood, however, that such description and drawing are merely illustrative of the invention, which is not limited in any way thereby or otherwise than by the appended claims.

Referring to the drawing, in which similar reference numerals refer to like parts,

Fig. 1 is a vertical sectional view of a heat treating apparatus according to my invention, and

Fig. 2 is a view of a second form of a heat treating apparatus embodying my invention.

In Fig. 1 of the drawing there is disclosed an apparatus and chamber according to my invention, the chamber comprising the upper wall 1, the side walls 2, 3 and the bottom wall 4. The lower wall 4 is formed with a central raised portion 5 defining two wells or recesses 6, 7 which are respectively located between the sides of the raised portion of the lower wall and the side walls 2, 3 of the chamber, and which are provided for a purpose to be explained hereinafter. An inlet port 8 is provided in the upper part of the chamber, preferably in the side wall 2, as illustrated, and an outlet port 9 is provided in the lower wall 4, preferably centrally of the

raised portion 5 thereof, these ports providing means for leading the strip into and out of the chamber. Within this chamber and at the upper part thereof are two pulleys 10, 11 from which respectively depend endless imperforate metallic belts 12, 13. The pulleys are so positioned with respect to each other that adjacent depending belt reaches 14, 15 are in face-to-face parallel relation and are spaced apart sufficiently to receive a metal strip 16 therebetween in face-to-face contactual engagement therewith. Idler rollers 17, 18 are mounted just above the raised portion 5 of the lower wall and are positioned at opposite sides of the outlet port 9. Other idler rollers 19, 20 are mounted just below and laterally outwardly from the rollers 17, 18, being respectively located at the inner and upper corners of the wells 6, 7. The lower part of the endless belt 12 is trained under the roller 17 and over the roller 19 whereby it is guided over the well 6, while endless belt 13 is trained under roller 18 and over roller 20 whereby it is guided over the well 7. Heating means for the belts, such as radiant tubes, are provided within the chamber and are illustrated at 21.

It will be understood that as the belts are heated they will become elongated. Any increase in the length of either of them will merely cause a part of the belt to travel downwardly into the well thereunder after it passes over the roller 19 to 20, thereby preventing dragging of the belts on the lower or other wall of the chamber and consequently preventing the marring of the belt which would be caused by such contact with the walls.

These wells or receptacles may also be provided in a vertical furnace of the type in which the effective heating lengths of the belts have been increased, for example in the manner disclosed and claimed in my co-pending application Serial No. 455,105. Such heating belts in a furnace provided with the slack-receiving wells of this invention are disclosed in Fig. 2 of the drawing. In this embodiment the parts of the belts which contact the metal strip are arranged in a circuitous path, as illustrated. The lower parts of the belts are trained over pulleys 30, 31 and 32, 33 in the same manner as is illustrated in Fig. 1 whereby the belts will be led above the wells or recesses 34, 35 which receive any slack therein due to stretching or otherwise.

While I have illustrated various forms which my invention may take, it will be apparent to those skilled in the art that other embodiments of the invention may be made and that im-

provements and changes may be made therein, all without departing in any way from the spirit or scope of the invention, for the limits of which reference must be had to the appended claims.

What is claimed is:

1. An apparatus for heat treating strip metal, comprising a furnace chamber, a plurality of endless, imperforate metallic belts in said chamber, means at the upper portion of said chamber for supporting said belts in such a manner that the belts depend from the supports in such positions that adjacent vertical reaches of the belts are in spaced face-to-face relation whereby a moving metal strip may be maintained therebetween in face-to-face contact therewith and whereby slack portions of the belts are caused at the lower ends thereof as the belts are elongated by heat, means for moving each belt along its endless path, means for heating the belts, the lower portion of the furnace chamber having spaced wells therein which are offset laterally with respect to the adjacent vertical reaches of the belts and within each of which the slack in one of the endless belts is received, and means for guiding that part of each endless belt which has moved out of contact with the strip to a position over and into one of said wells.

2. An apparatus for heat treating strip metal, comprising a furnace chamber having upper, lower and side walls, a plurality of endless, imperforate metallic belts in said chamber, means at the upper portion of said chamber for supporting said belts in such a manner that the belts depend from the supports in such positions that adjacent vertical reaches of the belts are in spaced face-to-face relation whereby a moving metal strip may be maintained therebetween in face-to-face contact therewith and whereby slack portions of the belts are caused at the lower

ends thereof as the belts are elongated by heat, means for moving each belt along its endless path, means for heating the belts, the lower portion of the furnace chamber being provided with a central raised portion having a port therein through which the metallic strip is adapted to pass, the raised portion forming with the opposite side wall of the furnace spaced wells which are offset laterally with respect to the adjacent vertical reaches of the belts and within each of which the slack in one of the endless belts is received, and means for guiding that part of each endless belt which has moved out of contact with the strip to a position over and into one of the wells.

3. A furnace chamber for a strip metal heating apparatus of the type in which two endless, imperforate metallic belts depend from supports in the upper portion of the furnace chamber in such positions that remote depending reaches of the belts are positioned adjacent opposite side walls of the furnace and adjacent vertical reaches of the belts are in spaced face-to-face relation whereby a moving metal strip may be maintained therebetween in face-to-face contact therewith and whereby slack portions of the belts are caused at the lower ends thereof as the belts are elongated by heat, said chamber comprising upper, lower and side walls, the lower wall having a central raised portion defining two wells which are located between the opposite sides of the raised portion and the opposite side walls of the chamber and which are offset laterally with respect to the adjacent vertical reaches of the belts, and within which wells slack in the belts is adapted to be received, and means for guiding that part of each endless belt which has moved out of contact with the strip to a position over and into one of said wells.
